UNITED STATES PATENT OFFICE.

CHARLES H. MELVIN, OF MOLINE, ILLINOIS, ASSIGNOR TO DEERE & COMPANY, A CORPORATION OF ILLINOIS.

PLOW.

1,137,881.

Specification of Letters Patent.

Patented May 4, 1915.

Application filed April 27, 1911, Serial No. 623,580. Renewed April 14, 1913. Serial No. 761,051.

To all whom it may concern:

Be it known that I, CHARLES H. MELVIN, a citizen of the United States, residing at Moline, in the county of Rock Island and 5 State of Illinois, have invented certain new and useful Improvements in Plows, of which the following is a specification, reference being had therein to the accompanying drawing.

- 10 This invention relates to improvements in plow bodies and especially in those of the type adapted for use on steam plows in which a number of bodies are secured to the same frame.
- 15 One of the objects of the invention is to provide a plow body having improved structural features and improved means for readily and quickly attaching or detaching the plow share to or from the other plow 20 parts.

In the accompanying drawings I have shown one embodiment of my invention. It is to be understood, however, that various changes in the construction and arrangement 25 of parts may be made within the scope of my invention.

Of the drawings, Figure 1 is a perspective view taken from beneath. Fig. 2 is a perspective view taken looking downward 30 from the rear. Fig. 3 is a fragmentary cross sectional view taken on the line 3—3 of Fig. 1. Fig. 4 is a detailed view of the transverse bracket.

Referring to the drawings, 1 represents 35 the plow point or share, 2 the moldboard, 3 the landside, and 4 the frog to which the landside, moldboard and share are connected. 5 is a standard to which the frog is secured and by means of which the plow 40 body is moved. This standard is indicated by dotted lines in Fig. 1.

The frog is bent or forged in the usual 45 way to provide two parts at an angle to each other. To one of these parts the moldboard is secured by bolts or rivets and to the other of these parts the landside is similarly secured. The plow share 1 has integrally formed moldboard and landside sections. The moldboard section 6 is adapted 50 to be supported by the moldboard part of the frog and to engage the forward edge of the moldboard in proper alinement. The landside section 7 is adapted to aline with the landside and to engage the landside part 55 of the frog.

On the inner side of the section 7 of the share there is located a lug 8. The lug

preferably consists of a staple formed of a round iron rod, the ends of which are passed through counter-sunk holes in the section 7 60 and riveted in place. If desired, however, the projections may be formed integrally with the share, or in any other way. The frog is provided with a slot 9 into which the lug 8 projects. The engagement of the 65 lug with the edges of the slot prevents any sliding or twisting of the share relative to the other parts of the plow body.

10 represents a brace or bracket which extends transversely of the plow body. At 70 the landside end of the brace there is formed a lug 11 by means of which the brace may be bolted to the landside. At the other end of the brace there are provided oppositely extending arms 12 and 13, the former of 75 which is engaged by a bolt 14 extending through the frog, and the latter of which is engaged by a bolt 15 extending through the moldboard. At the outer end of the arm 13 there is provided a forward extension 16 80 which gradually diminishes in thickness toward its end and which is provided with a notch 16^a adapted to receive the button 17 on the under side of the share. This button 17 is secured to the share by means of the 85 bolt 18, the threaded end of which is preferably riveted over to prevent removal. The button has a central hub and an outer flange adapted to closely engage the under surface of the projection 16. The hub and flange 90 parts of the button are preferably, but not necessarily, formed in one piece as indicated in the drawings.

19 represents a share retaining bolt pivotally secured at its forward end to the under side of the share preferably by means of a bolt 20. A notch 21 is formed in the lower edge of the brace 10 to receive the rear end of the bolt 19. Interposed between the brace 10 and a nut 22 on the retaining bolt 100 is a latch 23. This latch is pivoted at 24 to the upper side of the brace 10. A slot 25 permits the latch to move into the position indicated by full lines in the drawings. When in this position the bolt is held against 105 displacement from the notch 21 even though the nut 22 is not tightened.

In the preferred construction the brace 10 is reinforced by a lateral flange 26. For reinforcing the brace at the notch 21 there is 110 preferably provided a cross flange 27. 28 is a reinforcing flange along the edge of the arm 13 and the extension 16.

29 is an auxiliary brace secured at one end

to the rear part of the moldboard. The other end of the brace is secured to the bracket 10 at a point intermediate the landside and the notch 21.

- 5 To remove the share for sharpening or for replacement in the case of breakage, it is only necessary to loosen the nut 22 sufficiently to permit the latch 23 to be swung to the position indicated by dotted lines in
 10 Fig. 2. The bolt 19 may then be swung out of the notch and the share removed by one operation. In replacing the share it is first put in position with the projection 8 extending into the slot 9 and with the button 17 in the notch of the bracket extension 16. The bolt 19 is then swung about its pivot into the notch 21. After the latch 23 has been moved into its normal bolt retaining position, the nut 22 may be tightened and 20 the share drawn into its final position.

It will be observed that the engagement of the lug 8 with the edges of the slot 9 prevents any relative movement of the share relative to the landside part of the frog. 25 The engagement of the button 17 and the under side of the share with the bracket extension 16 prevents upward or downward movement of the share out of alignment with the moldboard.

- 30 The share retaining bolt 19 is normally at an angle to the line of contact between the share and the moldboard so that when the bolt is tensioned there is a tendency not only for movement of the share toward the 35 moldboard but also for movement of the share transversely of the moldboard to move the landside section of the share into engagement with the landside part of the frog. In order to permit such transverse movement the notch 16^a in the bracket extension 16 is preferably formed at an acute angle to the line of movement, as indicated by the section line 3—3 in Fig. 1.

What I claim is:

- 45 1. In a plow, the combination of a frog having two integral broad sheet-like parts at an angle to each other, a moldboard secured to and supported by one of the parts, a landside secured to and supported by the 50 other of the parts, a share having a section in alignment with the moldboard, and a transverse brace secured at one end to the landside and at the other end to the frog, and to the moldboard and to the share at 55 points beyond the edge of the frog.

2. In a plow, the combination of a frog having two integral broad sheet-like parts at an angle to each other, a moldboard secured to and supported by one of the parts, 60 a landside secured to and supported by the other of the parts, a share, a transverse brace secured at one end to the landside and at the other end to the frog, the moldboard and the share, and an auxiliary brace con-

3. In a plow, the combination of a frog 70 having two integral broad sheet-like parts at an angle to each other, a moldboard secured to and supported by one part, a landside secured to and supported by the other part, a share, means for securing the share to the other plow parts, and a transverse brace connected at one end to the landside and at the other end to the frog and to the moldboard at a point beyond the edge of the frog.

4. In a plow, the combination of a frog, having two integral broad sheet-like parts at an angle to each other, a moldboard secured to and supported by one of the parts, a landside secured to and supported by the other of the parts, a share, means for securing the share to the other of the plow parts, a transverse brace connected at one end to the landside and at the other end to the frog and to the moldboard at a point beyond the 90 edge of the frog, and an auxiliary brace connected at one end to the rear part of the moldboard and at the other end to the said transverse brace intermediate its ends the said brace being free from engagement with 95 other plow parts.

5. In a plow, the combination of a frog having an upper broad sheet-like part, a moldboard secured to the broad sheet-like part of the frog, a share, a bracket connected to the broad sheet-like part of the frog and to the moldboard at relatively remote points, the said bracket having an element extending at an angle to a line connecting the said points of connection, and means for securing the said element to prevent pivotal movement of the bracket about one or the other of the said points of connection, in a plane at an angle to that of the frog and mold-board.

6. In a plow, the combination with a 110 moldboard and frog of a detachable share, a bolt pivotally connected at its forward end to the share, a transversely extending bracket having a notch into which the rear end of the bolt may be swung about the said 115 pivot, means for retaining the bolt in the said notch, and means for tensioning the bolt to draw the share into place.

7. In a plow, the combination with a frog and a moldboard of a detachable share, a 120 bolt pivotally connected at its forward end to the share, a transversely extending bracket having a notch into which the bolt may be swung about the said pivot, a latch pivotally connected to the bracket and adapted to engage the bolt to hold it in the said notch, and means for tensioning the bolt to draw the share into normal position.

8. In a plow, the combination with a frog and a moldboard of a detachable share, a 18

5 bolt connected at its forward end to the share, a bracket provided with an aperture for receiving the rear end of the bolt and a forward extending notched projection adapted to engage the under side of the share, a device on the share arranged to enter the said notch and engage the under side of the projection, and means for tensioning the said bolt to draw the share into normal 10 position.

15 9. In a plow, the combination with a frog and a moldboard, of an apertured bracket secured to the frog and moldboard and having a forwardly extending projection, a detachable share adapted to engage the frog and moldboard and provided with means for engaging the upper and lower sides of the said projection to lock the share against relative upward or downward movement, a 20 bolt secured to the share and adapted to extend through the aperture of the bracket, and means for tensioning the bolt to draw the share into normal position.

25 10. In a plow, the combination with a frog and a moldboard of a detachable share, a bolt connected at its forward end to the share, a bracket having an aperture for the rear end of the bolt and provided with a forwardly extending notched projection, a device on the share having a central hub part adapted to enter the notch of the projection and a flanged part adapted to engage the under side of the projection, and means for tensioning the bolt to draw the share 30 into normal position.

35 11. In a plow, the combination of a frog, having two parts at an angle to each other, a moldboard secured to one of the parts, a landside secured to the other of the parts, a 40 detachable share, a bolt connected at its forward end to the share, a transverse bracket connected at one end to the landside and provided intermediate its ends with an aperture for receiving the rear end of the bolt, an auxiliary brace connected at one end to the rear part of the moldboard and at its 45 forward end to the said bracket intermediate its ends; and means for tensioning the said bolt to draw the share into normal position.

50 12. In a plow, the combination of a frog having two parts at an angle to each other, a moldboard secured to one of the parts, a landside secured to the other of the parts, a detachable share, a bolt connected at its 55 forward end to the share, a transverse bracket connected at one end to the landside and at the other end to the frog and the intermediate its ends with a notch for receiving the rear end of the bolt, and means for tensioning the bolt to draw the share into 60 normal position.

13. In a plow, the combination of a frog having two parts at an angle to each other,

a moldboard secured to one of the parts, a landside secured to the other of the parts, 65 a detachable share, a bolt connected at its forward end to the share, a transverse bracket connected at one end to the landside and at the other end to the frog and to the moldboard, the said bracket being provided 70 intermediate its ends with an aperture for receiving the rear end of the bolt, means for tensioning the bolt to draw the share into normal position, and means on the bracket for engagement with the share to hold it in 75 alinement with the moldboard.

14. In a plow, a land side; a mold board; a share comprising a land side section and a mold board section; a brace connected with the land side and with the mold board, the 80 brace having a slotted extension overlying the mold board section of the share, said section having a stud registering in the slot of the extension; a tie slidable transversely of the brace, the tie and the mold board section of the share having interengaging elements; and means upon the tie for engaging the brace to slide the tie.

15. In a plow, a frog having a slot; a land side and a mold board carried by the frog, 90 a share comprising a land side section and a mold board section, the land side section having a stud received in the slot; a brace connected with the land side and with the mold board, the brace having a slotted extension overlying the mold board section of the share, said section having a stud registering in the slot of the extension; a tie 95 slidable transversely of the brace, the tie and the mold board section of the share having interengaging elements; movable means cooperating with the tie and with the brace for sliding the tie; and another brace connecting the first specified brace with the mold board.

105 16. In a plow, a land side; a mold board; a share comprising a land side section and a mold board section; a brace connected with the land side and with the mold board, the brace having a slotted extension overlying 110 the mold board section, said section having a headed stud registering in the slot of the extension, the extension being tapered toward its free end to engage with the head of the stud; a tie slidable transversely of the 115 brace, the tie and the mold board section having interengaging elements; and means upon the tie for engaging the brace to slide the tie.

120 In testimony whereof I affix my signature, in presence of two witnesses.

CHARLES H. MELVIN.

Witnesses:

HARLAND E. RICH,
ANNA A. CONWELL.

It is hereby certified that in Letters Patent No. 1,137,881, granted May 4, 1915, upon the application of Charles H. Melvin, of Moline, Illinois, for an improvement in "Plows," an error appears in the printed specification requiring correction as follows: Page 3, at the end of line 57, insert the words *moldboard, the said bracket being provided*; and that the said Letters Patent should be read with this correction therein that the same may conform to the record of the case in the Patent Office.

Signed and sealed this 1st day of June, A. D., 1915.

[SEAL.]

J. T. NEWTON,

Acting Commissioner of Patents.
